SHIRT PACKAGING FORM

Philip F. Danziger, Milbrae, Calif., assignor to
 Market Industries Co., Inc., San Francisco,
 Calif., a corporation of California

Application November 24, 1951, Serial No. 258,027

5 Claims. (Cl. 223—71)

1

This invention relates to a shirt packaging form, and more particularly to the type of form employed in laundries for the packaging of collar-attached laundered shirts, although the form may be employed for packaging of new shirts if so desired.

Summarizing the invention, the form comprises a base portion about which the body of a shirt may be folded in the usual manner; a back panel hingedly connected to the base portion and adapted to overlie the back of the collar of the shirt, a cover part hingedly connected to the back panel and adapted to overlie the collar of the shirt, and a side panel hingedly connected to each side edge of the cover part and adapted to overlie a side of the shirt collar. By such arrangement, a protecting box is provided about the shirt collar when the form is set up. Each of the side panels preferably has means for interlocking engagement with cooperable means on the form to maintain the side panel in an upright position relative to the base portion when the form is set up, to thus obviate collapsing of the collar protecting box. Also, the front end of each of the side panels is preferably constructed so as to be insertable underneath the cover part outside of the shirt collar, to provide a supporting brace for the cover part, and thus maintain the protecting box relatively rigid.

From the preceding, it is seen that the invention has as its objects, among others, the provision of an improved shirt packaging form which when set up fully protects the laundered collar of the shirt, which is strong structurally so that it can be made out of relatively light material, which is of simple and economical construction, and in which the arrangement and construction of the parts is such that the form can be rapidly and easily set up. Other objects of the invention will become apparent from a perusal of the following detailed description.

Referring to the drawings:

Fig. 1 is a plan view of the inside face of the single sheet of material from which the shirt packaging form is made, and illustrating the same in blank form, before it is set up;

Fig. 2 is an isometric view of the set up form of Fig. 1 without a shirt thereon;

Fig. 3 is a fragmentary sectional elevation taken in a plane indicated by line 3—3 in Fig. 2;

Fig. 4 is a view similar to Fig. 2 but looking at the set up form from a different angle, and with a shirt folded thereon.

The form is composed of a single sheet of material, preferably paperboard, but it may be made

2

of any other equivalent material which can be creased, and folded to enable the form to be set up in the manner to be described. It has an upper transversely extending crease line 2 and a lower crease line 3 parallel thereto. These crease lines may be score lines but are preferably so-called cut-score lines to facilitate folding along the lines. All other crease lines subsequently described are also preferably of the cut-score type, unless otherwise designated. The positions of the various creases, panels and other parts of the form described herein are their positions in the set-up condition of the form.

Crease lines 2 and 3 divide the form into a base portion 4 which is generally rectangular in shape and has substantially parallel side edges 6, a back panel 7 hingedly connected to base portion 4 along crease line 3, and a cover part 8 hingedly connected to back panel 7 along the crease line 2. Base portion 4 is adapted to support the body of a shirt folded around the same in a conventional manner; and back panel 7 is adapted to be folded along the hinge connection formed by crease line 3, to an upright position relative to base portion 4, so as to overlie the back of collar 9 of the shirt outside of the collar to thus provide protection for the back of the collar. In this connection, the spacing between the pair of crease lines 2 and 3, is such that back panel 7 when set up is wide enough to accommodate the usual variations in the height of shirt collars.

Cover part 8 is adapted to be folded along crease line 2 so as to be positioned substantially parallel to base portion 4, and thus overlie collar 9 of the shirt to protect the top edge of the collar in the set up position of the form. It is provided with an inspection opening 11 to enable the laundry mark on the skirt to be readily visible when the shirt is packaged on the form.

The side edges of cover part 8 are defined by a pair of crease lines 12 extending transversely at a right angle with respect to both of crease lines 2 and 3. Crease lines 12 provide hinged connections along each side edge of cover part 8 for a side panel 13, each of which is adapted to be folded in an upright position relative to cover part 8 and base portion 4 in the set up position of the form, to overlie the outer side of the shirt collar. Thus, when the form is set up with the shirt folded on base portion 4, base portion 4, back panel 7, cover part 8 and side panels 13 provide a protecting box enclosing the outer sides of collar 9 as well as the back, bottom and top thereof to protect the same thoroughly.

It will be noted that each of crease lines 12 is spaced inwardly with reference to the associated side edge 6 of base portion 4, so that the width of cover part 8 between the side edges thereof defined by crease lines 12 is less than the width of base portion 4. As a result, in the set up position of the form, the bottom edges 14 of side panels 13 can engage the body of the folded shirt so as to be supported by base portion 4 to maintain rigidity.

To hold each side panel 13 in an upright position so that cover part 8 will be prevented from collapsing when the set up shirt forms are stacked, means is provided on each side panel for interlocking engagement with cooperable means on the form. For this purpose, the rear end 16 of each side panel has a tab 17 in the form of a hook extending therefrom; each hook being adapted to interlock in an associated opening in the back panel 7. Each of such openings is formed by a cut line 18 leaving a hinged flap 19 which normally closes the opening in the blank form of the device.

Each cut line 18 is so shaped as to permit ready insertion of the tab 17 into the opening and engagement of the hook of the tab along edge portion 21 of the opening. The natural resiliency of the material, which tends to cause the side panels to swing outwardly in the set up position of the form, maintains fixed engagement of the hook on tab 17 in the associated opening of the back panel.

To provide enhanced rigidity, the front end 22 of each side panel 13 is so constructed as to be insertable underneath cover part 8 and outside of the shirt collar, in the set up position of the form, so as to provide a supporting brace for cover part 8 at each front corner thereof. For this purpose, a gusset type connection is provided between the front end 22 of each side panel 13 and the front portion of cover part 8 adjacent such front end.

Each of the gusset type connections is formed by a diagonally extending crease line 23 on cover part 8, and a crease line 24 extending transversely across side panel 13 and meeting crease line 23 at a point on crease line 12. Thus, the front portion of each crease line 12 and crease line 23 form a triangular gusset flap 26 which can be folded underneath cover part 8 in the set up position of the form with the result that the front end portion 22 of each side panel 13 becomes automatically tucked underneath the cover part 8 by virtue of the inward folding along transversely extending crease line 24, hence forming a supporting brace for the cover part at the front end of each side panel 13 in the set up position of the form.

From the preceding, it is seen that when the form is set up over the folded shirt, side panels 13 are substantially rigidly held and braced in upright position to maintain substantially rigid the above described protecting box. With sacrifice of rigidity, the above described bracing at the front of side panels 13 may be omitted, but it is preferred because of the greater strength and support for cover part 8 which it provides.

Preferably, the form is also provided with wings which are insertable between the parts of the fold of the collar. The front edge 31 of cover part 8 in the set up position of the form, is preferably arcuate in shape and has hingedly connected thereto centrally thereof a member 32, also arcuate in shape, which has laterally extending wings 33 adapted to be inserted between the parts of

the fold of the collar in the set up position of the form; the wings 33 being separated from cover part 8 by arcuate cuts which define the front edge 31 of the cover part. Member 32 is preferably hingedly connected to the front edge 31 of cover part 8 by means of a tab 34 formed from parallel cuts 36 in cover part 8 and which is hingedly connected to the cover part along crease line 31, and to the wing member 32 along crease line 36. The described hinged connection of wing member 32 to cover part 8 provides a very flexible connection between cover part 8 and wing member 32, to enhance ready insertion of the wings 33 within the fold of the collar.

To facilitate flexing or bending of wings 33 about the inner part of the fold of the collar when they are inserted within the fold thereof, a plurality of longitudinally extending plain score lines 39 are provided on the wing member 32, so that wings 33 can be easily flexed along such score lines to conform to the configuration of the collar. Score lines 39 are substantially parallel but because of the curvature of wing member 32, they extend substantially radially with reference to such curvature. With wings 33 inserted within the fold of collar 9, support for the collar obtains to maintain its shape; and since the sides as well as the back of the collar are completely enclosed within the previously described protecting box, the collar is substantially completely protected.

A tab 41 is preferably provided adjacent each front corner of wing member 32; and each of these tabs is hingedly connected to member 32 along a crease line 42. Tabs 41 serve the purpose of providing means for ready grasping by the operator to facilitate insertion of the wings 33 within the fold of the collar. During such operation, the operator bends the tabs along crease lines 42; and as a result, such tabs also serve as a means frictionally engaging the body of the folded shirt to maintain the wings in relatively fixed position. As usual in forms of the character related, a paper band 43 may be positioned about the folded shirt and base portion 4, to hold the body of the shirt in position.

I claim:

1. A shirt packaging form composed of a single sheet of paperboard having a pair of substantially parallel crease lines to provide a base portion to support the body of a folded shirt, a back panel hingedly connected to said base portion along one of said crease lines and adapted to overlie the back of the collar of said shirt, and a cover part hingedly connected to said back panel along the other of said crease lines and adapted to overlie the collar of said shirt; a side panel hingedly connected to each side edge of said cover part along a crease line extending transversely with respect to said first mentioned crease lines and adapted to overlie a side of said shirt collar whereby said side panels, said back panel and said cover part are adapted to provide a protecting box about said shirt collar, each of said transversely extending crease lines being spaced inwardly with respect to the associated side edge of said base portion whereby the width of said cover part is less than the width of said base portion so that said side panels can be supported by said base portion in the set up position of said form, each of said side panels being free of substantial projection beyond the front end of said cover part, and the front end of each of said side panels and the front portion of said cover part adjacent such front end

having a gusset type connection enabling the front end of each of said side panels to be inserted underneath said cover part outside of said shirt collar to provide a supporting brace for said cover part.

2. A shirt packaging form composed of a single sheet of paperboard having a pair of substantially parallel crease lines to provide a base portion to support the body of a folded shirt, a back panel hingedly connected to said base portion along one of said crease lines and adapted to overlie the back of the collar of said shirt, and a cover part hingedly connected to said back panel along the other of said crease lines and adapted to overlie the collar of said shirt; a side panel hingedly connected to each side edge of said cover part along a crease line extending transversely with respect to said first mentioned crease lines and adapted to overlie a side of said shirt collar whereby said side panels, said back panel and said cover part are adapted to provide a protecting box about said shirt collar, each of said transversely extending crease lines being spaced inwardly with respect to the associated side edge of said base portion whereby the width of said cover part is less than the width of said base portion so that said side panels can be supported by said base portion in the set up position of said form, each of said side panels being free of substantial projection beyond the front end of said cover part, the front end of each of said side panels being insertable underneath said cover part outside of said shirt collar to provide a supporting brace for said cover part, the rear end of each of said side panels having means for interlocking engagement with cooperable means on said back panel, and a member in front of the front ends of said side panels having laterally extending wings insertable within the fold of said collar and hingedly connected to the front edge of said cover part.

3. A shirt packaging form composed of a single sheet of paperboard having a pair of substantially parallel crease lines to provide a base portion to support the body of a folded shirt, a back panel hingedly connected to said base portion along one of said crease lines and adapted to overlie the back of the collar of said shirt, and a cover part hingedly connected to said back panel along the other of said crease lines and adapted to overlie the collar of said shirt; a side panel hingedly connected to each side edge of said cover part along a crease line extending transversely with respect to said first mentioned crease lines and adapted to overlie a side of said shirt collar whereby said side panels, said back panel and said cover part are adapted to provide a protecting box about said shirt collar, each of said transversely extending crease lines being spaced inwardly with respect to the associated side edge of said base portion whereby the width of said cover part is less than the width of said base portion so that said side panels can be supported by said base portion in the set up position of said form, each of said side panels being free of substantial projection beyond the front end of said cover part, the front end of each of said side panels being insertable underneath said cover part outside of said shirt collar to provide a sup-

porting brace for said cover part, the rear end of each of said side panels having means for interlocking engagement with cooperable means on said back panel, and a member in front of the front ends of said side panels having laterally extending wings insertable within the fold of said collar and hingedly connected to the front edge of said cover part, said wings having spaced apart parallel score lines to facilitate flexing of said wings about said collar and also hingedly connected grasping tabs.

4. A shirt packaging form comprising a base part adapted to support the body of a folded shirt, a back part hingedly connected to said base part and adapted to overlie the back of the collar of said shirt, a cover part hingedly connected to said back part and adapted to overlie the collar of said shirt, and a side part hingedly connected to each side edge of said cover part and adapted to lie at the outer side of said shirt collar, each of said side parts being free of substantial projection beyond the front end of said cover part, means connected to the rear of each of said side parts cooperable with said back part to provide for rigidity of said form at the rear thereof, a member in front of the front ends of said side parts having laterally extending wings insertable within the folds of said collar and hingedly connected to the front edge of said cover part, and bracing means in addition to said latter member adapted to cooperate with said cover part adjacent the front of said cover part to provide for rigidity of said form at the front thereof.

5. A shirt packaging form comprising a base part adapted to support the body of a folded shirt, a back part hingedly connected to said base part and adapted to overlie the back of the collar of said shirt, a cover part hingedly connected to said back part and adapted to overlie the collar of said shirt, and a side part hingedly connected to each side edge of said cover part and adapted to lie at the outer side of said shirt collar, each of said side parts being free of substantial projection beyond the front end of said cover part, a tab at the rear end of each of said side parts for interlocking engagement in an opening in said back part with said side parts extending in planes normal to said back part, and a member in front of the front ends of said side parts having laterally extending wings insertable within the fold of said collar and hingedly connected to the front edge of said cover part, the front end portion of said cover part adjacent the front end portion of each side part being provided with a diagonally extending crease line to form a substantially triangular gusset flap adapted to be folded against the underside of said cover part to provide a brace for said cover part.
